C. D. BONSALL

CAR ROOF

Original Filed April 17, 1922

Fig. 1.

Fig. 2.

Fig. 3.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Original application filed April 17, 1922, Serial No. 553,645. Divided and this application filed February 26, 1923. Serial No. 621,217.

To all whom it may concern:

Be it known that I, CHARLES DAVID BONSALL, a citizen of the United States, a resident of the city of Pittsburgh, county of Allegheny, and State of Pennsylvania, have invented a certain new and useful Improvement in Car Roofs, of which the following is a specification.

This invention relates to heavy gage steel car roofs and is a division of my pending application for patent Serial No. 553,645, filed April 17, 1922.

The principal object of the present invention is to increase the strength and rigidity of the roof by improving the seam construction thereof. Other objects are reduced weight, simplicity of construction and cheapness of manufacture.

The invention consists principally in securing hollow stiffening members to the outside of the roof over the upstanding joints between adjacent sheets, whereby said stiffening members cooperate with said upstanding joints to form exterior hollow box-girders. The invention further consists in the parts and arrangements and combinations of parts hereinafter described and claimed.

In the accompanying drawing, wherein like symbols refer to like parts wherever they occur,

Fig. 1 is a plan view of a portion of a car roof embodying my invention;

Fig. 2 is an enlarged transverse cross-section through one-half of the roof, the section being taken between joints on the line 2-2 in Fig. 1; and,

Fig. 3 is a transverse cross-section through one of the box-girder joints at the ridge on the line 3-3 in Fig. 1.

The roof shown in the accompanying drawing comprises heavy gage roof sheets 4 which extend from eaves to eaves of the car and slope downwardly on opposite sides of the ridge to form a pitch roof. The eaves ends of the roof sheets are supported on and rigidly secured to the outwardly extending flanges of angle-bar side plates 5 by means of rivets 6 and are preferably provided at their eaves ends with depending drip flanges 7 that overhang the outer edges of said side plates.

The side margins of the roof sheets are flanged up, as at 8, and laid in contact along

side of each other and rigidly connected together by horizontal rivets 9. As shown in the drawing the side flanges 18 are of substantially uniform height from ridge to points adjacent to the eaves where they are curved downwardly and merge into the plane of the sheets at the eaves ends thereof. The upstanding seam flanges 8 of adjacent roof sheets are straddled by inverted U-shaped stiffening members or seam caps 10 provided with lateral base flanges 11 that rest on and are welded or secured by rivets 12 to the body portions of the roof sheets on opposite sides of the riveted seam or joint. These stiffening members which constitute outside carlines, extend from eaves to eaves of the car and are of gradually decreasing height on opposite sides of the ridge; and the eaves ends of said stiffening members or outside carlines are closed by curving their eaves end portions downwardly from points adjacent to the eaves at their ends where they merge into the plane of the lateral base flanges 11. The eaves end portions of these stiffening members are secured to the side plates by the securing rivets 6 for the eaves ends of the roof sheets and are provided with depending flanges 13 that overlap the adjacent end portions of the eaves flanges 7 of adjacent sheets.

Running boards 14 extend longitudinally of the car at the ridge and are securely bolted to the horizontal flanges of running board saddles 15 arranged crosswise of the roof. The running board saddles rest on and are riveted or otherwise rigidly secured to the tops of the exterior stiffening members or carlines.

By the arrangement described the inverted channel-shaped stiffening ribs serve as frame members to brace and stiffen the roof and thus accomplish the various functions of an outside carline. At the same time, said outside carlines cooperate with the roof sheets to form hollow box-girders that stiffen the sheets against buckling and increase the load carrying capacity of the roof. It is particularly noted that by forming hollow box-girders above the roof, the roof plates are placed in tension under a vertical load, thereby eliminating the tendency of the plates to bend or buckle, and the top portions of the stiffening ribs are placed in compression.

and have sufficient rigidity to withstand compressive stresses. It is also noted, that the outside carlines cover the rivets that secure together the upstanding seam flanges of adjacent sheets, and thereby prevent leakage around the rivets.

Obviously, my invention admits of considerable modification in the form of seam and in the shape of the seam cap. For instance, the seam cap may be of uniform height and width throughout; or, if desired, said seam cap, or the base flanges thereof, may vary in width from ridge to eaves.

15. What I claim is:

1. A car roof comprising a plurality of roof sheets connected together along their adjacent margins by rigid joints, and cap strips of inverted channel shape covering said joints, said cap strips being positively secured to adjacent sheets on opposite sides of the joints and far enough therefrom to form with such adjacent sheets hollow box-girders.
2. A car roof comprising a plurality of roof sheets connected together along their adjacent margins by rigid joints, and cap strips of inverted channel shape straddling said joints, said cap strips having lateral base flanges resting on and positively secured to adjacent sheets, whereby said cap strips cooperate with said roof sheets at a distance from such joints to form hollow box-girders.
3. A car roof comprising a plurality of roof sheets having upstanding marginal flanges connected together flatwise to form rigid joints, and cap strips of inverted channel shape straddling said joints, said cap strips having lateral base flanges resting on

and positively secured to said sheets on opposite sides of said joints at a distance therefrom, whereby said cap strips cooperate with said roof sheets to form hollow box-girders.

4. A car roof comprising roof sheets extending from side plate to side plate and rigidly secured thereto, said roof sheets having upturned side marginal flanges that are rigidly secured together to form joints, and cap members of inverted channel shape straddling said joints, said cap members extending from side plate to side plate with their ends rigidly secured thereto and having lateral base flanges resting on and positively secured to said roof sheets on opposite sides of said joints at a distance therefrom, whereby said cap members cooperate with said roof sheets to form hollow box-girders.

5. A car roof comprising roof sheets extending from side plate to side plate and rigidly secured thereto, said roof sheets having upturned side marginal flanges that are rigidly secured together to form joints, and cap members of substantially inverted U-shaped cross-section straddling said joints, said cap members extending from side plate to side plate with their ends rigidly secured thereto, said cap members being of greater depth at the ridge than at the eaves, and having outwardly extending lateral base flanges resting on and positively secured to said roof sheets on opposite sides of said joints, whereby said cap members cooperate with said roof sheets to form hollow box-girders.

Signed at New Kensington, Pa., this 20th day of February, 1923.

CHARLES DAVID BONSALL.

Certificate of Correction.

It is hereby certified that in Letters Patent No. 1,481,825, granted January 29, 1924, upon the application of Charles David Bonsall, of Pittsburgh, Pennsylvania, for an improvement in "Car Roofs," an error appears in the printed specification requiring correction as follows: Page 2, claim 2, lines 32 and 33, strike out the words "at a distance from such joints" and insert the same to follow after the word "sheets" in line 31; and that the said Letters Patent should be read with this correction therein that the same may conform to the record of the case in the Patent Office.

Signed and sealed this 18th day of March, A. D., 1924.

[SEAL.]

KARL FENNING,
Acting Commissioner of Patents.
